(57) **CLAIM**

The ornamental design for a power tool case holder, as shown and described.

DESCRIPTION

FIG. 1 is a front perspective view of a power tool case holder;

FIG. 2 is a front elevation view of a power tool case holder;

FIG. 3 is a rear elevation view of a power tool case holder;

FIG. 4 is a right side view of a power tool case holder;

FIG. 5 is a left side view of a power tool case holder;

FIG. 6 is a top view of a power tool case holder;

FIG. 7 is a bottom view of a power tool case holder; and,

FIG. 8 is a rear perspective view of a power tool case holder. The shade lines in the Figures show contour and not surface ornamentation.

The broken lines showing portions of the design in all figures are included for the purpose of illustrating environment and do not form a part of the claimed design.
